ABSTRACT

A cover for a door lock assembly having a knob assembly and a bolt assembly. The cover has a pair of side plates integral with a front plate and is formed of sheet material such as sheet steel. The cover is rigidly secured to the door and has an opening for receiving the bolt assembly and a pair of openings for receiving the knob assembly.

COVER FOR DOOR LOCK ASSEMBLY

BACKGROUND OF THE INVENTION

1. Field of the Invention

This invention relates to the field of art of guards for door locks.

2. Prior Art

In widely used door lock assemblies a tumbler barrel is located within the door knob. In order to open the door a key is inserted into the tumbler and by turning the key or the knob the latching bolt is actuated to open the door. Such types of lock assemblies have become widely used in inside and outside doors as they are usually less costly than lock assemblies having a separate dead bolt and a latching bolt. However, these lock assemblies have caused problems of longitudinal splitting of the door panel and cracking or splitting of the wood between the latching bolt and the door sides. Such door splitting has been caused by a force applied to the latching bolt when the door is forcefully pushed when the bolt is engaged.

SUMMARY OF THE INVENTION

A cover for a door lock assembly having a knob assembly and a bolt assembly. The cover is formed of sheet material having plates integral with a front plate. The front plate has an opening for receiving the bolt assembly and each of the side plates has an opening cooperating with an opening in the door which receives the knob assembly. The lock cover is rigidly secured to the door to protect the door from damage resulting from force applied to the bolt assembly.

In the method of installation, an opening is formed in the door for the knob assembly and another opening is formed for the bolt assembly. The door is covered adjacent these openings with a one piece lock cover having openings cooperating with the knob assembly opening and the bolt assembly opening. The covering is then rigidly secured in place.

BRIEF DESCRIPTION OF THE DRAWINGS

FIG. 1 is a front view of a door carrying the lock cover of the present invention;

FIGS. 2 and 3 show the lock cover of FIG. 1 in more detail;

FIG. 4 illustrates another embodiment of the invention in which material is removed from the door; and

FIGS. 5 and 6 illustrate in detail another embodiment of the invention in which a single slot is formed to receive the lock assembly.

Referring now to FIGS. 1-3 there is shown an outside door 10 having a lock assembly 11 installed therein. Lock assembly 11 includes a front door knob 12 having a key hole opening 13, a front door rose 14, and a rear door knob and rose (not shown). Lock assembly 11 is commonly called a cylindrical lock assembly or a key-in-the-knob lock. When a key is inserted in opening 13 it engages a tumbler barrel (not shown) and by turning the key or the knob, latching bolt 15 is actuated. Bolt 15 is part of a bolt assembly 21 which is horizontally disposed in opening 18 of door 10. Rose 14 covers one type of conventional cylindrical lock clamping assembly comprising a pair of clamping members having lips.

In the installation of lock assembly 11 as particularly shown in FIG. 3, an opening 20 is drilled through door 10 from front side 16 to rear side 17. Opening 18 for the lock assembly is then drilled from front edge 19 of door 10 until it meets opening 20. In order to install the door lock cover 25 of the present invention, door edge is mortised with recesses 22 and 23 at a depth equal to the thickness of cover 25.

Cover 25 is formed of a single sheet of material, preferably metal to form a front plate 26 and side or cover plates 27 and 28. Side plates 27 and 28 have openings 30 and 31 respectively formed therein which cooperate with opening 20 when lock cover or guard 25 is fixed in position. Front plate 26 has a rectangular opening 33 which receives a front face plate member 34 of bolt assembly 21 which is mortised in door edge 19 by recess 36. The depth of recess 36 is approximately half

the thickness of plate 34 so that the outer edge of plate 34 is flush with the outer edge of plate 26.

As shown in FIG. 2, cover 25 is secured in place by wood screws 37-39 which pass through openings 40-42 in side plate 27 and threadedly engage side 16 of door 10. Side plate 28 has similar openings (not shown) for receiving wood screws which engage side 17. In order to further secure lock cover 25, front plate 26 has openings 44 and 45 for receiving wood screws 47 and 48 respectively which engage door edge 19.

10 In the method of installation, the openings 18 and 20 are first formed by drilling and the cover 25 is fixed in position by the respective wood screws. The lock assembly 21 and the knob assembly which includes the roses and knobs are then installed in position. Specifically, the flat outer surfaces of side plates 27 and 28 adjacent openings 30 and 31 receive lips of the clamping members. The clamping members are tightened onto the side plates and in this way secure the knob assembly in place with a portion of the clamping assembly extending through door opening 20.

20 Thus with cover 25 secured in position, edge 19, cover 25 and plate 34 are flush and lock assembly 11 is mechanically protected. As the door is pushed, a force normal to the longitudinal axis of bolt 15 is transmitted by way of plate 34 and the vertical edge of cover opening 33 to front plate 26 of cover 25. In this manner such force is received by plate 26 which is reinforced by side plates 27 and 28. Thus the substantially strong lock cover 25 receives the force rather than the relatively thin and fragile wood door portions 50 and 51 which are on either side of bolt assembly 21. In this way, upon application of a high value force the wood portions are not broken. In addition, without cover 25 the force would have the effect of separating wood portions 50 and 51 thereby cracking or splitting the edge 19 of door 10 along a longitudinal line at the edge center.

30 An additional advantage of the present invention is that since plate 26 covers and effectively hides wood portions 50 and 51, any damage to these portions during installation of assembly 11 does not mar the attractiveness of the door. Since the clamping assembly lips abut and only frictionally connect to side plates 27a and 28, lock assembly 11 may easily be removed for service without removing cover 25.

40 As an alternative method of installation in accordance with the invention, instead of centering and drilling opening 18, FIG. 3 an opening 55 may be formed by sawing, for example, from edge 19 to opening 20 as shown in FIG. 4. In this manner there is avoided the necessity of actually drilling opening 18 in the exact center of edge 19 which requires a skilled craftsman. Alternatively, opening 18 may be drilled and if not properly done opening 55 may then be sawed. It will be seen that opening 55 comprises parallel, horizontal plane walls 56 and 57 which are spaced apart a distance greater than the vertical height of bolt assembly 21. In the door of FIG. 4, recesses 22 and 23 are provided and for ease of installation the opening to receive plate 34 is formed of horizontal recesses 58 and 59 which extend between door sides 16 and 17. As in FIG. 3 the depth of recesses 58 and 59 is approximately half the thickness of plate 34 so that the outer edge of plate 34 is flush with the outer edge of plate 26. In this manner lock assembly 11 may be easily installed in openings 20 and 55 of FIG. 4 and the open spacings between plate 34 and sides 16 and 17 are covered by front plate 26.

50 Referring now to FIGS. 5 and 6 there is shown a simple method of installation of a lock assembly known as Quick Set made by Quick Set Company, 516 East Santa Anna Street, Anaheim, California. By the use of lock cover 25a of the present invention, the Quick Set lock assembly may be installed without drilling any holes. Specifically, opening 55 of FIG. 4 is extended from edge 19a toward the rear of door 10a to form slot opening 55a having upper and lower flat parallel, horizontal walls 56a and 57a respectively. Openings 56a-57a may be formed for example by sawing door 10a and are spaced apart a sufficient distance to receive the rectangular shaped Quick Set lock assembly. Cover 25a is fixed in position

in the manner previously described by screws 37a, 39a, 47a, and 48a for example. After that, the lock assembly (not shown) is inserted in opening 55a and plate 34a fixed in position in recesses 58a and 59a. The rose 14a and knob assembly 12a are then placed in position on door side 16a with similar parts being assembled on door side 17a.

In the Quick Set cylindrical lock assembly, rose 14a and the opposing rose on door side 17a each have conventional clamping lips and these roses themselves comprise the clamping members which are then tightened on the cover 25a. It will be understood that side plate openings 30 (30a) and 31 (31a) are of magnitude to pass through most of the clamping assembly but of magnitude small enough to form the adjacent surfaces abutting the clamping member lips.

It will be understood that door lock covers or guards 25 and 25a may be shaped in different decorative forms as for example, in the rounded shape, shown in FIGS. 1-3 or the more rectangular shape, shown in FIGS. 5 and 6. It will be understood that with a solid door, shown in FIGS. 1-3, opening 41 may extend to the rear of cover 25 remote from front plate 26 while in a hollow door, openings 40a and 42a are positioned to engage the solid portion of the door which extends from edge 19a a conventional distance. In addition, covers 25 and 25a may be made of suitable material such as cold rolled steel and may be one-sixteenth of an inch in thickness, for example.

What is claimed is:

1. A cover for a cylindrical lock mounted in a door, said cylindrical lock having a bolt assembly and a knob assembly, said knob assembly including a clamping assembly having a pair of clamping members having lips, said bolt assembly including a face plate with outer edges and having an opening for a bolt, comprising

5 a pair of side plates integral with a front plate formed of sheet material, said side plates each having completely flat outer surfaces and having no keyhole openings, said side and front plates having substantially equal and constant transverse dimensions,

10 said front plate including a front surface having an interruption, said interruption being substantially equal in dimension to the dimension of the outer edges of said face plate for receiving said face plate in said interruption and in flush relationship with said front surface, each of said side plates having an opening cooperating with an opening in said door,

15 said flat outer surfaces of said side plates adjacent said side plate openings for receiving said lips of said clamping members which members are adapted to be tightened onto said side plates thereby to secure said knob assembly in place with a portion of said clamping assembly extending through said door, said clamping member lips abutting and only frictionally connected to said side plates, each of said side plate openings being of magnitude large enough to receive and pass through most of said clamping assembly and of magnitude small enough to form said adjacent surfaces abutting said clamping member lips, and means for rigidly securing said lock cover to said door to protect said door from damage resulting from force applied to said bolt.

2. The lock cover of claim 1 in which said front and side plates are formed of a single piece of sheet metal.

3. The lock cover of claim 1 in which there are provided additional openings in said front and side plates for receiving fastening members to secure said lock cover to said door.
